(57) **CLAIM**

The ornamental design for a sash lock, as shown and described.

DESCRIPTION

FIG. 1 is a top view of the present invention where the hood of the sash lock covers the keeper.

FIG. 2 is a front view of the sash lock of the present invention showing the lock and keeper.

FIG. 3 is a bottom view of the sash lock of FIG. 1.

FIG. 4 is a rear view of the sash lock of FIG. 1.

FIG. 5 is a left side view of the sash lock of FIG. 1.

FIG. 6 is a right side view of the sash lock of FIG. 1.

FIG. 7 is a rear perspective view of the sash lock of FIG. 1.

FIG. 8 is a front perspective view of the sash lock of FIG. 1.

FIGS. 9A and B are top views of an alternative embodiment of the sash lock and keeper of the present invention where hood of the sash lock does not cover the keeper.

FIG. 10A is a front view of the sash lock of FIG. 9A

FIG. 10B is a front view of the sash lock of FIG. 9B.

FIG. 11A is a bottom view of the sash lock of FIG. 9A

FIG. 11B is a bottom view of the sash lock of FIG. 9B

FIG. 12A is an end view of the sash lock of FIG. 9A.

FIG. 12B is an end view of the sash lock of FIG. 9B.

FIG. 13A is a left side view of the sash lock of FIG. 9A.

FIG. 13B is a left side view of the sash lock of FIG. 9B.

FIG. 14A is a right side view of the sash lock of FIG. 9A.

FIG. 14B is a right side view of the keeper of FIG. 9B.

FIG. 15A is a perspective view of the sash lock of FIG. 9A; and,

FIG. 15B is a perspective view of the keeper of FIG. 9B.
